Primary Examiner — Cynthia Ramirez*Assistant Examiner* — Tamara L Hahn(74) Attorney, Agent, or Firm — Taylor English Duma LLP(57) CLAIM

I claim the ornamental design for a diamond-shaped brush head, as shown and described.

DESCRIPTION

FIG. 1 is a perspective view of the diamond-shaped brush head.

FIG. 2 is a right-side elevation view thereof.

FIG. 3 is a left-side elevation view thereof.

FIG. 4 is a front elevation view thereof.

FIG. 5 is a rear elevation view thereof.

FIG. 6 is a top plan view thereof; and,

FIG. 7 is a bottom plan view thereof.

The broken lines showing a ferrule and a handle in FIGS. 1-5 & 7 are to show environment and form no part of the claimed design.

1 Claim, 4 Drawing Sheets(56)
